BENDING DIE

Roy F. McMahan, Louisville, Ky.

Original application March 26, 1936, Serial No. 70,933, now Patent No. 2,201,193, dated May 21, 1940. Divided and this application May 3, 1940, Serial No. 333,073

2 Claims. (Cl. 153—1)

This invention relates to improvements in bending dies, and is a division of my earlier application, Serial Number 70,933, filed March 26, 1936, and entitled "Hanger and method of attaching same," now Patent 2,201,193, May 21, 1940.

In the aforesaid application, there is disclosed a hanger formed from sheet metal and the method of securing the same to a wooden bar. The hanger has incorporated therewith a pair of relatively spaced arms, between which a wooden bar is positioned with its side portions in abutting relation with corresponding portions of the spaced arms. The arms have a length greater than the thickness of the wooden bar, and the extremities of the arms are bent in a novel manner so as to provide a new method of securing a metal member to a wooden bar. This method comprises bending the unsupported portions of the arms, inwardly and downwardly over a surface of the bar and at the plane of the said surface; then simultaneously bending the extremity of each of the said arms downwardly and inwardly with respect to its arm and into approximately arch-shape while the extremity is spaced from the said surface; continuing both of said bending movements until the free edges of the said extremities contact with and are forced into the said surface during the aforesaid arch-forming operation; and retaining the abutting relation of the arms with the said bar during the aforesaid bending operations.

Therefore, it is the object of this invention to provide a simple and effective bending die for performing the steps of the aforesaid method in a simple and economical manner.

Accordingly, it is a further object of this invention to provide a bending die having a construction suitable for practicing the salient characteristics of the method on articles other than the hanger illustrated in my aforesaid application.

These and other objects will be apparent to those skilled in the art as the following description is read in connection with the accompanying drawing, in which:

Figure 1 is a vertical sectional-view of the die block illustrating substantially the first step of bending the arms inwardly and downwardly over the surface of the wooden bar 12;

Figure 2 is a similar vertical sectional-view illustrating the forming tool 16 advanced in its downward movement relative to the stationary anvil 191. In Figure 2 substantially the begin- 55

ning of the second step of bending the arms into approximately arch-shape is illustrated;

Figure 3 is likewise a vertical sectional-view illustrating the forming tool 16 further advanced in the arch-forming operation;

Figure 4 is also a vertical sectional-view and illustrates the forming tool 16 still further advanced in the arch-forming operation;

Figure 5 is likewise a vertical sectional-view 10 illustrating the forming tool 16 substantially beginning its operation of forcing the extremities 17 into the wooden bar 12;

Figure 6 is a similar vertical sectional-view 15 and illustrates the forming tool 16 substantially completing the operation of forcing the extremities 17 into the wooden bar 12;

Figure 7 is a partial plan view of the completed article, on a slightly reduced scale, as viewed from the outer face of the metal member 14; and

Figure 8 is a vertical sectional-view illustrating the relation of the arms 15 of the metal member 14 relative to the wooden bar 12 prior to operation thereon by the forming tool 16.

In the foregoing drawing only vertical sectional-views of the bending die were presented, and it is to be understood that the cross-sectional contours thereof are substantially the same throughout the length of the die. It is to be further understood that the forming tool 16 is provided with a suitable mounting means, so that the same may be operatively connected to any actuating mechanism for imparting a vertical sliding movement thereto. Similarly, it is to be understood that the anvil 191, or stationary portion of the die, is secured to a stationary table in operative relation with the forming tool 16.

The specific bending die illustrated in the drawing, is primarily employed for securing a sheet-metal bracket to a wooden bar, which bar may be a chair rung, table leg or similar hardware used in the manufacture of furniture. Therefore, it is to be understood that the contour of the anvil 191, the depending arms 161, and the plane of the forming contours 18 may be altered to accommodate the particular shape of the metal and wooden members. In this respect, it will be apparent that the teachings of this invention may be utilized in attaching a single arm 15 to a wooden bar 12, or the wooden bar may comprise several pieces placed between the arms 15. Accordingly, it is important to observe the relation existing between the inner faces of the depending arms 161 relative to the outer faces of the arms 15; the relation existing

between each extremity 17 and its corresponding forming contour 18, and the relation existing between each projection 19 and its corresponding extremity 17, when the same is forced into the wooden bar 12, as illustrated in Figure 5. For these specific relations reference is directed to the drawing.

Thus, in specifically describing the particular forming tool illustrated in the accompanying drawing, I do not desire to be limited other than by the scope of the appended claims. Therefore, although the means for retaining the arms 15 in abutting relationship with the corresponding sides of the wooden bar 15 comprises arms 161 secured to the forming tool 16 in the preferred embodiment of my invention, such arms may be dispensed with, and the metal member placed into a channel formed in the anvil 191, or separate clamping members may be forced into engagement with the arms 15 by action of the forming tool 16.

However, in practicing the method disclosed in my co-pending application Serial No. 70,933, it was observed that it is desirable, for most applications, to provide the movable forming tool 16 with depending guide-arms 161.

From the foregoing, it will be apparent that the bending die of the illustrated embodiment is adapted to secure a metal member to a wooden bar, wherein the metal member has a portion thereof formed into substantially a channel shape having legs or arms 15 longer than the thickness of the wooden bar, as illustrated in Figure 8, and, as illustrated in Figure 7, the arms 15 extend longitudinally along the corresponding sides of the wooden bar.

In Figure 6 the forming tool 16 is shown in its closed position relative to the anvil 191, and the final condition of the arms 15 relative to the wooden bar 12 is clearly illustrated.

The bending die of the present invention is not to be confused with the usual tool employed to fold a metal arm laterally against the side face of a bar, or in which the free end of an arm is clinched into a wooden bar, as the contour 18 of the present invention is constructed and arranged to bend the arm into arch shape while the extremity 17 is spaced from the outer surface of the bar 12, as progressively illustrated in Figures 3, 4 and 5, and then forcing the extremity 17 into the bar 12 during the arching operation, as illustrated in Figure 6. Thus, it will be apparent that, between the stages illustrated in Figures 5 and 6, the extremity 17 moves in an arcuate path, that is, the unsupported end 15a slides longitudinally along the arched contour 18 until the extremity 17 is pushed into the bar and beneath the outer surface thereof. During these final stages, the corresponding projection 19 penetrates the outer surface of the bar and assures a thorough local compression of the bar beneath the arched arm.

Therefore, the salient feature of the bending die is the arched contour 18 and its relation to the extremity 17, and the relative depression of the face 19a so as to provide a projection 19 for penetrating the outer surface of the wooden bar to provide the final securing operation.

Thus, to secure a metal member 14 having a pair of oppositely disposed arms 15, as illustrated in Figure 8, the bending die comprises an anvil 191 upon which the metal member 14 is placed, as indicated in Figure 1. The bending die also comprises a forming tool 16 having a pair of depending arms 161 adapted to engage

forcibly the arms 15, and to retain the same in abutting relation with corresponding sides of the bar 12. The extremities of the depending arms 161 are rounded, or tapered, so as to assure proper engagement of the arms 15 under reasonable manufacturing variation.

Forming contours 18, of substantially semi-circular shape, are provided within the forming tool adjacent each corresponding depending arm 161, and these contours 18 extend longitudinally along the forming tool, for a distance sufficient to accommodate the arms 15 of the metal member 14.

The inner face 19a of the forming tool is depressed to form projections 19, and these projections merge into the corresponding forming contours 18 substantially diametrically opposite the point of tangency of the inner face of the corresponding depending arm 161, and have their ends pointed for penetrating the wooden bar substantially adjacent the arched portion of the corresponding arm 15. The projections 19, like the forming contours 18, extend longitudinally along the forming tool, so as to accommodate the arms 15 of the metal member 14.

In operation, the metal member 14 containing the bar 12 is placed upon the anvil 191, and it is to be understood that the anvil 191 is provided with guides for locating the arms 15 of the member 14 relative to the forming tool 16.

The forming tool is then moved downwardly, and the inner faces of the depending arms 161 forcibly engage the arms 15 for retaining the same in abutting relationship with the corresponding sides of the bar 12.

As the forming tool advances downwardly, the extremities 17 engage and slide laterally over the arched surfaces of the corresponding forming contours 18, and the unsupported ends 15a of the arms 15 bend inwardly and about the top corners of the bar, as illustrated in Figure 1. This bending operation continues until the extremities arrive at points substantially beyond corresponding mid points of the arches, whereupon each of the ends 15a begin to assume an arch shape, as illustrated in Figure 2.

During the arching operation, the extremities continue to slide laterally over the arched surfaces of their corresponding forming contours 18, by reason of the relative stiffness of the metal. This action is illustrated in Figures 2, 3 and 4.

The final stage of the arching operation is completed while each extremity is spaced from the outer surface of the bar, and preferably slightly before the extremities contact the said outer surface, as evidenced by Figures 4 and 5.

Each end 15a at this stage is substantially in face contacting relation with its corresponding forming contour 18, and, as the downward movement of the forming tool 16 continues, each end 15a slides over the surface of the corresponding forming contours 18 in substantially face contacting relationship, whereupon the extremities 17 are brought into contact with and forced into the outer surface of the bar 12, as illustrated in Figures 5 and 6. Thus, in forcing the extremities into the bar 12, such operation is accomplished by sliding each end 15a laterally over the surface of its corresponding forming contour 18.

This securing operation provides a minimum rupture for the fibres of the wood beneath the arched ends 15a.

Thus, careful analysis of Figures 5 and 6, in view of the foregoing, will reveal that the projec-

tions 19 penetrate the bar 12 adjacent their corresponding arched end 15a and support the same until the securing operation is completed, as illustrated in Figure 6. Whereupon the forming tool 16 is withdrawn and the assembled article removed from the anvil 19.

While I have shown and described what I considered to be the most practical embodiment of my invention, it is to be understood that various changes in construction may be made under the scope of the appended claims.

Having thus described my invention, I claim:

1. In apparatus for securing the legs of a sheet metal channel to a rectangular wooden bar disposed within the trough of the channel, having its side and bottom faces, respectively, engaging the inner faces of the legs and base of the channel, and having its top face substantially below the free end edges of the legs, the combination of upper and lower relatively movable pressure applying members; opposed longitudinal dies on the said pressure applying members; one of said dies having a longitudinal opening of substantially the same width as that of the sheet-metal channel with substantially vertical side walls for slidably engaging the outer faces of the legs of the channel, the said one die having two semi-circular concave-surfaces formed therein at the base of the said opening, the outer edge of each semi-circular surface each respectively being tangent with the corresponding vertical wall of the opening and extending longitudinally therewith, the said one die also having its medial portion between the respective concave-surfaces cut below the inner edges of each respective concave surface; the other of said die members having a longitudinal portion substantially equal in width to that of the opening, the said other die member also having a flat surface for engaging the base of the sheet-metal channel, and vertical sidewalls for slidably engaging the vertical walls of the said opening; the vertical side walls of the said opening each respectively engaging the outer faces of the legs of the channel during the relative movement of the said dies for retaining the inner faces of the legs in abutting relation with

the respective side faces of the bar, and guiding the free end edges of the legs into engagement with each respective concave surface to provide a lateral bending of the extremity of each leg inwardly and downwardly over the top face of the wooden bar and at the plane thereof, and upon further relative movement of the said dies to bend simultaneously the extremity of each leg downwardly and inwardly with respect to the legs of the channel into approximately arch-shape while each extremity is spaced from the top face of the bar, and upon a still further relative movement of the said dies to continue both of the bending movements until the free end-edges of the legs contact with and are forced into the top face of the wooden bar during the arch forming operation.

2. In apparatus for retaining the legs of a sheet-metal channel in abutting relationship with a wooden member while bending the extremities into approximately arch shape and continuing said bending until the free end-edges of legs contact with and are forced into a surface of the bar, the combination of upper and lower relatively movable pressure applying members; opposed longitudinal dies on the said pressure applying members; one of said dies having a longitudinal opening of substantially the same width as that of the sheet-metal channel, and having substantially vertical side walls for slidably engaging the outer faces of the legs of the channel, the said one die also having two semi-circular concave-surfaces formed therein at the base of the said opening, the outer edge of each semi-circular surface each respectively being tangent with a vertical wall of the opening and extending longitudinally therewith, the said one die also having its medial portion between the concave surfaces cut below the inner edges of each respective concave surface; and the other of said die members having a longitudinal portion substantially equal in width to that of the opening, and also having a face for engaging the base of the channel, and likewise vertical sidewalls for slidably engaging the vertical walls of the opening.

ROY F. McMAHAN.
